UNITED STATES PATENT OFFICE.

WILLIAM OTTAWAY, OF AURORA, ILLINOIS, ASSIGNOR TO AURORA AUTOMATIC MACHINERY COMPANY, OF CHICAGO, ILLINOIS, A CORPORATION OF ILLINOIS.

CARBURETER.

1,105,687.

Specification of Letters Patent.

Patented Aug. 4, 1914.

Application filed April 14, 1913. Serial No. 760,929.

To all whom it may concern:

Be it known that I, WILLIAM OTTAWAY, a citizen of the United States, and a resident of Aurora, in the county of Kane and State 5 of Illinois, have invented certain new and useful Improvements in Carbureters; and I do hereby declare that the following is a full, clear, and exact description thereof, reference being had to the accompanying drawings, and to the letters of reference marked thereon, which form a part of this specification.

This invention relates to carbureters and means for conveying combustible fluid from 15 the same to the cylinders of multiple cylinder internal explosion motors, and more especially to the means whereby the introduction of combustible fluid to each cylinder of the motor may be separately regulated, 20 so that firing will occur in each cylinder alike, or the explosions in the various cylinders will occur with uniformity and regularity and in such a manner as to obtain the highest degree of efficiency.

25 The principal object of the invention is to provide a simple, economical and efficient carbureter and means for conveying and regulating the supply of combustible fluid from a carbureter or source of fluid supply 30 to the cylinder or cylinders of an engine.

Other and further objects of the invention will appear from an examination of the following description and claims and from an inspection of the accompanying drawings.

The invention consists in the features, combinations, and details of construction herein described and claimed.

In the accompanying drawings, Figure 1 40 is a view in central vertical section of a carbureter and manifold constructed in accordance with my improvements; Fig. 2, a detail view in horizontal section, taken on line 2 of Fig. 1 looking in the direction of 45 the arrow, and showing a plurality of tubes forming auxiliary passages for conveying the combustible fluid to the cylinders of a motor, and the means for controlling the passages formed by such tubes; and Fig. 3, 50 a detail view in horizontal section, taken on line 3 of Fig. 1, showing the tubular or sleeve valve mechanism and the inner casing or tube by which the tubular valve mechanism of the carbureter is surrounded.

55 In the accompanying drawings, my im-

proved manifold or means for conveying combustible fluid from a carbureter to the cylinders of a multiple-cylinder internal combustion motor is shown in combination with or so constructed as to form a part of 60 a carbureter made in accordance with my invention described and shown in a pending application Serial No. 745,318, filed January 31, 1913, for an improvement in carbureters.

In order to enable this invention and the 65 construction and mode of operation of a device embodying the same to be readily understood so as to enable those skilled in the art to make and use the invention, it is here shown and will be described in connection 70 with a carbureter of the type described and shown in said co-pending application. It will, however, be readily understood by those skilled in the art that the manifold, or improved means herein described and shown, 75 for conducting the combustible fluid or mixture from the mixing chamber or carbureter to the cylinders of a multiple-cylinder internal combustion engine or motor is adapted to be used in connection with any desired 80 type or form of carbureter or device for intermixing hydrocarbons and air in such proportions as to form a suitable combustible fluid for use in connection with internal combustion engines or motors.

85 In constructing a device in accordance with my invention and improvements, I provide a casing *a* having an inner tubular portion or inner casing walls *b* encircled by the outer casing or walls and forming therewith an annular float chamber *c* in which is located an annular float *d*. The float shown in the drawings is in the form of a hollow, annular shell which encircles the inner casing portion *b*, and is encircled by the outer 90 casing *a* and adapted to move or float freely upward and downward within the casing or float chamber. An annular bottom casing portion *e*, which may be made in one integral piece with the outer casing portion or walls *a*, forms the main bottom of the casing and float chamber and is provided with an upwardly extending, screw-threaded flange *f* in screw-threaded engagement with the screw-threaded bottom 100 end of the inner casing member or tube *b*, as shown in Fig. 1. A cover *g* of annular construction encircles the upper portion of the inner casing or tube member *b* and is secured thereto and to the outer casing mem- 110

ber *a* in any desired suitable manner. The upper portion *h* of the inner casing or tube *b* projects through and upward beyond the cover member *g* and is provided with outer screw threads as indicated in Fig. 1. The improved manifold, induction device, conduit or means for conducting combustible fluid from the mixing chamber to the cylinders of a motor, and which is hereinafter more particularly described, is adapted to be secured to the carbureter by being mounted in threaded engagement with the screw-threaded portion *h* of the tubular member *b*, or by other securing means of any desired, ordinary or well known form. A feed tube *n* forming a combustible fluid or hydrocarbon supply passage *o*, is mounted in position to extend upwardly on the inside of the inner casing member or tube *b* and is supported by means of a supporting member or tube body portion *p* having radial arms *q* which are secured to the casing bottom *e* by means of screws *r* or other similar securing means. And a casing bottom or sub-bottom *s* having side wall portions *t* is mounted beneath the annular casing bottom member *e* and provided with a central aperture through which the lower end of the feed tube may project. The lower projecting end *u* of the feed tube is provided with inner and outer screw threads, and a nut *v* is mounted in threaded engagement with the outer screw threads of this downwardly projecting end portion of the feed tube and in supporting engagement with the bottom member *s* so as to securely hold the tube and said bottom member in position and in rigid engagement with each other. A plug *w* is mounted in threaded engagement with the bottom end of the tube and forms a closure for the same. The bottom member *s* with its side walls *t* forms an air reservoir passage or space *y*, and is provided with one or more air supply passages *z* communicating with said space. A suitable screen *2* of reticulated material or wire netting is mounted on the interior of the passage, reservoir, or compartment *y* in position to admit air to and exclude dust, sand, grit, and other foreign substances from the interior of the carbureter or mixing chamber. A hollow tubular portion *3* is provided on one side of the casing having a passage *4* through the inner wall thereof which communicates with the interior of the float chamber *c*, as shown in Fig. 1. The upper end of this vertical, tubular portion is closed by means of a plug *5*. To the lower end of the tubular portion *3* is secured a coupler member or valve casing *6*, the upper end of which is in threaded engagement with the tubular member *3*, and the lower portion of which is provided with screw threads and adapted to be secured in threaded engagement with a suitable coupler member or sup-

ply pipe connected with a source of hydrocarbon or combustible fluid supply. The coupler member or valve casing *6* has a central, axial opening or passage *8* leading therethrough, and controlled by suitable valve mechanism comprising a valve-operating lever *13*, but which mechanism may be of any desired suitable form adapted to permit the valve to be raised by means of the float *d* and valve-operating lever when the hydrocarbon or combustible fluid becomes sufficiently low in the float chamber to permit the float to so operate the lever *13* as to raise the valve. The float chamber is provided with an outlet opening *22* which is covered by a screen *23*. This opening communicates with the inner passage *o* in the feed tube *n* by way of a passage *24* formed by a tube *25*, one end of which is connected with the feed tube *n* and the other end of which is connected with the bottom of the casing and float chamber outlet *22* by means of a coupler member or screened cap and pipe-connecting member *26*. The screen-supporting cap *26* and pipe *25* thus form a passage leading from the float chamber to the interior of the feed tube *n*. The feed tube *n* is provided at its upper end with a fluid supply nozzle *27* having combustible fluid supply passages or nozzle passages *28* which lead from the passage *o* into the mixing chamber *38* of the carbureter.

A throttle valve, which is, by preference, in the form of a butterfly valve *34*, is rockingly mounted in the upper portion *i* of the casing upon a horizontal rock-shaft *35* which is journaled or rotatably supported in the casing (see Figs. 1 and 2). This throttle valve is adapted to be operated or turned to open or closed or any desired intermediate position to correspond with the speed of operation of the motor or engine in any desired, ordinary, or known manner and by means of operating mechanism of any desired type known to those skilled in the art.

In the device shown in the accompanying drawings, a tubular valve bushing member *43* of smaller diameter than the inner stationary tubular casing member *b* is mounted inside of and in concentric relation to the latter, so as to provide an annular air space or air supply passage *45* between said parts *43* and *b* which air passage communicates with the air space *42* located below the level of the nozzle and below the mixing chamber *38*, and is adapted to be connected with the mixing chamber by auxiliary high-speed air inlet openings hereinafter described.

Mounted on the inside of and with its outer peripheral surface in sliding engagement with the inner peripheral surface of the tubular member *43*, is an endwise movable tubular valve member *49* having a bottom or tapered conical wall portion *56* provided with main air inlet openings *57* there-

in, as indicated in Figs. 1 and 3. This endwise movable tubular member 49 is provided with a peripheral laterally projecting annular flange 59 at its lower portion adapted to 5 close the main air inlet opening 60 which leads into the mixing chamber, and which opening is formed by the lower open end of the tubular valve bushing 43 when the member 49 is in raised position, or in the position which it occupies when the throttle valve 34 is closed or when the device is operating under low-speed conditions, (see Fig. 1). The flange 59 is adapted to admit air through the opening 60 when the endwise 10 movable valve member 49 is lowered so that said flange is below and out of engagement with the lower open portion of the valve bushing or rotatably mounted tubular valve member 43. A bottom conical tubular portion or sleeve 39 upon and in fixed relation to the lower end of the inner tubular valve member 49, forms a tapered annular air supply passage 41 leading from the air space 42 to the mixing chamber 38 and which is at 15 all times open. The rotatably mounted valve member or bushing 43 is provided with any desired number of auxiliary high-speed air inlet ports 47, as indicated in Fig. 3, and the endwise movable inner tubular 20 valve member 49 is provided with a corresponding number of auxiliary high-speed air inlet openings or ports 48 adapted to communicate with the ports 47 when the throttle valve 34 is in open position, and the 25 tubular valve member 49 at one extremity of its movement—for instance, in its lowered position—thus providing auxiliary air inlet passages leading through ports 47 and 48 from the main air supply passage 45 into the 30 mixing chamber, when the device is in operation under high-speed conditions and the throttle valve 34 is open. The rotative valve member or bushing 43 is also provided with a peripheral auxiliary air inlet opening 65, 35 and the inner valve bushing or member 49 with a corresponding peripheral auxiliary opening 66 for the admission of low-speed air or auxiliary air to be used when the device is in operation under low-speed conditions, 40 said openings being adapted to register or form an open auxiliary air inlet passage for low-speed air when the openings or ports 47 and 48 for admitting high-speed air are closed. The openings 65 and 66 are adapted 45 to be closed by the movement of the endwise movable valve member 49 to the position which it occupies when the throttle valve 34 is open or, in other words, when the device is in operation under high-speed conditions, 50 An air inlet passage 67 which is adapted to communicate with the openings 65 and 66, when open, is provided with a valve 68 adapted to be adjusted or operated by means of a thumb nut 69, or other suitable means, 55 to any desired position for regulating the 60 effectual area of the opening 67 for admitting low-speed air. The tubular rotative valve member 43 which is provided at its lower end with laterally projecting peripheral guiding lugs or arms 46 having spaces 70 therebetween for admitting incoming air to the space or passage 45, is adapted to be rotated by means of an operating stem or handle 50 to any desired adjusted position, for regulating or changing the width of the 75 high-speed auxiliary air passages formed by the ports 47 and 48 and without changing the low-speed air passage 67 leading to the ports 65 and 66,—in a direction circumferentially of the tubular valve members 43 80 and 49. Segmental shields or plates 53 and 54 are so mounted and movable with the stem 50 as to at all times close the opening in the casing through which the stem 50 extends, the segmental plate 54 being of resilient material and adapted to form a spring which serves to yieldingly hold the plate 53 in position to close said opening through 85 which the stem 50 extends.

The cylindrical valve member 49 is supported by a connecting rod or plunger 61, the lower end of which is pivotally connected with said cylindrical valve member 49 by means of a horizontal pivot or shaft 62 (see Fig. 1), and the upper end of which is operatively connected with the throttle valve 34 by means of lugs 63 which are secured to the valve 34, and a horizontal pivot 64 mounted in said lugs and in pivotal supporting engagement with the plunger or connecting rod 61, or by any desired suitable securing means which may be of any ordinary or well known form. 90

The endwise movable valve member 49 is thus supported and adapted to be operated automatically with or by means of the throttle valve 34 or simultaneously with the manual operation of the throttle valve, so as to open the high-speed auxiliary air inlet passages to the mixing chamber 38 and close the low-speed air inlet ports when the endwise movable valve member 49 is in the position which it occupies at one extremity of its movement—for instance, in lowered position—with the throttle valve open. It obviously follows that the auxiliary high-speed air inlet ports will be closed and the low-speed air inlet ports opened when the throttle valve is in closed position or the device operating under low-speed conditions. 105

The regulation of the proportions of liquid hydrocarbons and air admitted and intermixed may thus be controlled by regulating or controlling the admission of air, and the admission of high-speed air and low-speed air through separate or independent auxiliary inlet passages for such auxiliary high-speed air and low-speed air, respectively, may be regulated by separately adjustable regulating or controlling means, so that the 110 120 125 130

mixture or proportions of liquid hydrocarbons and air for high-speed conditions and for low-speed conditions, respectively, may be independently regulated, and may be varied with respect to each other as desired by separately adjustable means.

A carburetor constructed as above described is adapted to operate as set forth in the pending application above referred to, to which reference is made for a more detailed description of the device and the arrangement and operation of the parts above described.

A head, manifold, casing or conduit 70, for conducting combustible fluid to the combustion chamber of an engine or to each of the combustion chambers or cylinders of a multiple-cylinder engine, is provided and connected with the main casing or body *a* of the carburetor, which latter may, as already suggested, be of any desired, ordinary or known type. The head, manifold or casing, when in the form shown in the drawings, comprises in its construction a neck portion *i* and any desired number of branch pipes or casing portions *j* which may be integral with the neck *i* or secured to said neck portion in any desired, suitable, or known manner, so as to form any desired number of communicating or diverging connected passages or branch passages 72 all communicating with the main mixture outlet passage 71 formed by the neck or tubular portion *i*, and each leading to or adapted to communicate with a different explosion chamber or cylinder.

The opposite or diverging ends of the tubular portions *j* of the manifold, head or casing are provided with suitable means for connecting the passage or passages formed thereby with the combustion chamber or chambers, respectively, of an engine. This connecting means may consist of a pipe coupling *l* secured to the branch pipe *j* and having internal screw threads *m* adapted to be secured in threaded engagement with a threaded pipe leading to a cylinder of an engine, or with a suitable connecting sleeve, nipple, or pipe union member. The pipe coupling *l* for each of the branch tubular portions or branch pipes *j* is connected with the tubular member *j* in any suitable manner, for instance, by being mounted rotatably in engagement with an expanded end portion of the same. The casing or neck portion *i* thus forms a main combustible fluid outlet passage which communicates with the mixing chamber 38 and in which the throttle valve 34 may be mounted as indicated in the accompanying drawings.

A single valve-controlled passage comprising the passage 71 or passage portions 71 and 72 is of course sufficient for a single cylinder motor, and may be used in connection with an auxiliary tube 73 or by-pass or

passage 74 for conducting low-speed combustible fluid directly from the mixing chamber and provided with a regulating device constructed as described, or adapted to be adjusted independently of the main throttle valve which controls the high-speed combustible fluid passage. The connected but separate and distinct mixture outlet branch passages or passage portions 72, however, are each adapted to lead to a different one of a plurality or series of cylinders or explosion chambers of a motor located at unequal distances from the carburetor or combustible fluid supply, and which cylinders for this or any other reason may fire unequally or in an irregular manner. Or there may be a lack of uniformity, strength, or regularity in the explosions in one or more chambers or cylinders, or relatively weak explosions in one or more cylinders as compared with others, more especially when operating at low-speed. It is therefore very desirable to provide simple and efficient means whereby the flow of the mixture or combustible fluid to any cylinder or through any induction or combustible fluid passage leading to any explosion chamber may be regulated with respect to and independently of any other cylinder or cylinders. It is particularly desirable to provide regulating means and passages adapted to enable the supply or flow of combustible fluid for operating a multiple-cylinder motor, or other form of engine, at low-speed to be regulated independently of the valve mechanism for controlling the main mixture outlet or induction passage, through which the main supply of combustible fluid passes to the cylinders for operating at high-speed. It is also desirable to, at the same time, provide a desired number of auxiliary passages or by-passes having suitable independently adjustable means for regulating the flow of combustible fluid for low-speed operation independently of the valve-controlled main mixture outlet passage leading from the mixing chamber and through which the combustible fluid for operating under high-speed conditions passes.

It is obvious that there may be as many branches *j* and branch passage portions or passages 72 as there are cylinders to be supplied with combustible fluid from the carburetor with which the manifold or casing 70 is connected. For each branch passage 72 or branch pipe or tube *j* in excess of a single branch passage or pipe, a tube 73 is provided, one end of which communicates with the portion of the mixing chamber located intermediate the throttle valve 34 and the air inlet passage or passages of the mixing chamber, or, in other words, with the mixing chamber proper, so as to form an auxiliary combustible fluid discharge passage or by-pass 74 leading directly from the mixing

chamber around or independently of the throttle valve 34 into the mixture outlet passage or a branch portion of the mixture outlet passage at a point intermediate the throttle valve and the cylinder or combustion chamber with which such branch passage portion or branch pipe is to be connected. Each of these tubes 73, or the by-pass 74 formed thereby, is provided with means for regulating the effectual area or transverse area of such passage, or by-pass. The regulating means here shown consists of an adjustable threaded regulating screw 75 mounted in threaded engagement with a suitable similarly threaded support or boss 76 upon the corresponding auxiliary or by-pass tube and in position to extend into the passage 74 formed by the tube, so that by turning the screw in one direction the effectual area or transverse area of the passage or by-pass formed by the tube is reduced, and by turning the screw in the opposite direction the effectual area or transverse area of the passage is increased to any desired extent, limited only by the maximum size or area of the passage. A seat 76' in the portion of each tube opposite the side through which the screw extends is adapted to admit and to fit closely in engagement with the end of the screw when the latter is in passage-closing position so that the flow of fluid through the passage may be entirely prevented, when desired.

From the foregoing it will be seen that each of the tubes 73 forms an auxiliary combustible fluid discharge passage leading from a portion of the mixing chamber or outlet passage of the carburetor intermediate the throttle valve and the air inlet opening or openings of the mixing chamber, and that the auxiliary discharge passages or by-passes thus formed each communicate with a different diverging branch passage or branch portion of the main valve-controlled mixture outlet passage, and that each of the auxiliary passages is adapted to communicate with a separate or distinct combustion chamber, independently of the position or operation of the throttle valve. The auxiliary passages thus formed by the tubes 73 are adapted to conduct all or substantially all of the combustion fluid which is to be used when the device is in operation under low-speed conditions or when the throttle valve is closed. In other words, each of the auxiliary passages thus formed by the tubes 73 is adapted to form a conduit or by-pass for low speed combustible fluid, and the regulating means or screws 75 for the auxiliary passages or by-passes are adapted to enable the effectual area or flow of combustible fluid through the auxiliary passages to be controlled or regulated independently of the throttle valve, and the throttle valve may be entirely closed, if desired, during the op-

eration of the device, when the engine to be supplied is operated at low-speed, or, in other words, when the device is in operation under low-speed conditions.

I claim:

1. In a device of the character described, the combination of a mixing chamber provided with a plurality of mixture discharge passages adapted to communicate with the cylinders of an internal combustion engine, a throttle valve located intermediate of the mixing chamber and said mixture discharge passage, and a plurality of auxiliary mixture discharge passages communicating with said mixing chamber and with each of said discharge passages intermediate of the throttle valve and the cylinders of the engine. 70

2. In a device of the character described, the combination of a mixing chamber provided with an air inlet opening, a plurality of branch mixture outlet passages communicating with the cylinders of an internal combustion engine, a throttle valve adapted to control the discharge of the mixture from said mixing chamber, and a plurality of auxiliary mixture outlet passages connecting each of said branch passages with the mixing chamber intermediate of said throttle valve and the outlet opening of said mixing chamber, and a valve in each of said auxiliary passages. 80

3. In a device of the class described, the combination of a casing forming a main fluid passage, a throttle valve rotatively mounted on the inside of the main passage, 100 a plurality of branch pipes all communicating with a portion of the main passage located on one side of the throttle valve, and a plurality of auxiliary tubes each having its outlet end connected with a separate branch pipe, and each having its inlet end communicating with the interior of a portion of the casing located on the opposite side of such throttle valve from the branch pipes. 105

4. In a device of the class described, the combination of a head forming a main combustible fluid passage having an inlet opening at one end adapted to communicate with a mixing chamber and provided with a plurality of diverging branch passages communicating with the main passage, a throttle valve rotatively mounted on the inside of the main passage intermediate said inlet opening and said branch passages, a plurality of tubes each connected at one end with the main passage at a point intermediate the valve and the inlet end of the main passage and each connected at its opposite end with a separate branch passage, independently adjustable regulating means for each by-pass for controlling the effectual area thereof, a main carburetor casing, and means for connecting said head with the main casing of the carburetor. 110 115 120 125 130

5. In a device of the class described, the combination of a mixing chamber, a casing forming a mixture outlet passage for said mixture chamber, and provided with a plurality of discharge openings, a plurality of branch pipes connected with said discharge openings of the casing, each of said branch pipes being adapted to communicate with a separate combustion chamber of an engine, 10 a throttle valve located intermediate said casing and the mixing chamber, a plurality of by-pass tubes communicating with the mixing chamber and with each of said pipes, and an independently controlled valve in each of said by-pass tubes. 15

In testimony that I claim the foregoing as my invention I affix my signature in the presence of two witnesses, this 3rd day of April, A. D. 1913.

WILLIAM OTTAWAY.
